UNITED STATES PATENT OFFICE.

JOHN F. O'CONNOR, OF CHICAGO, ILLINOIS, ASSIGNOR TO WILLIAM H. MINER, OF CHAZY,
NEW YORK.

DRAFT-RIGGING.

1,300,459.

Specification of Letters Patent. Patented Apr. 15, 1919.

Application filed November 27, 1916. Serial No. 133,564.

To all whom it may concern:

Be it known that I, JOHN F. O'CONNOR, a citizen of the United States, residing at Chicago, in the county of Cook and State of Illinois, have invented a certain new and useful Improvement in Draft-Rigging, of which the following is a full, clear, concise, and exact description, reference being had to the accompanying drawings, forming a part of this specification.

This invention relates to improvements in draft riggings.

The object of the invention is to provide a draft rigging for railway cars, and more particularly a draft rigging of the spring type, having relatively cheap stop members formed from steel plates.

In the drawing forming a part of this specification, Figure 1 is a longitudinal section of a portion of a draft rigging illustrating my improvements. Fig. 2 is a horizontal sectional view of the structure illustrated in Fig. 1 and taken on the line 2—2 thereof. Fig. 3 is a transverse, vertical section, taken on the line 3—3 of Fig. 1. And Fig. 4 is a detail view illustrating one of the blanks from which my improved stop member is formed.

In said drawing, 10—10 denote draft sills of a car underframe to which are secured my improved stop plates A, A. Each of the latter is formed from a blank of the shape illustrated in Fig. 4. As there shown, the blank is of generally rectangular form having recesses 11—11 on each edge thereof, thus leaving four corner shoulders 12—12. The blank is centrally perforated as indicated at 13, for the purpose hereinafter described, and is also slotted at its front edge as indicated at 14. The blank, cut to the shape indicated in Fig. 4, is then bent substantially along the lines 15—15, thereby rendering the stop plate of substantially U-shape in cross section, as clearly indicated in Fig. 3. When so bent, the shoulders 12—12 will extend toward each other, thus forming upper and lower front and rear stop shoulders 16—16. The stop plates are secured to the sills by suitable means such as the rivets shown. The stop plate above described is designed more particularly for a spring gear of the twin type, that is, one employing front and rear followers 17—17

and vertical twin arranged springs 18—18, the latter each consisting of inner and outer 55 nested coils.

To operatively connect the gear with the draw bar 19, a horizontal yoke 20 is provided, the arms of the latter being slotted to receive the coupler key 21, the latter also 60 extending through elongated slots 22 in the sills and extending partly into the recesses 14 of the stop plates.

To limit the movement of the gear and prevent setting of the springs, I employ a 65 stationary key 23 which extends transversely between the springs 18 and through slots 24 in the side arms of the yoke, the slots 13 in the stop members and corresponding slots 25 in the sills. The key 23 is stationary and so spaced from the front and rear followers that the latter will engage with said key at the end of the permissible movement of the draw bar in either buff or draft. A saddle plate 26 is used to properly support the gear. 75

From the preceding description, it will be seen that the stop members can be made very cheaply from steel plates and form efficient stop members for the followers to engage. 80 Furthermore, said stop members, when applied to the sills, act as reinforcing members for the latter and increase the bearing area for the fixed key 23 which serves as a limiting stop, thus distributing the shocks 85 over a greater area of the sills.

I claim:

1. In a draft rigging, the combination with draft sills, a draw bar, a yoke, and cushioning means, of stop members secured 90 to said sills, each stop member comprising a plate bent to U-shape in vertical cross section with the arms extending horizontally, said arms having inwardly projecting shoulders. 95

2. As an article of manufacture, a stop member for draft riggings, said member consisting of a plate bent to U-shape in vertical cross section, the arms of the U having inwardly extending shoulders at the corners 100 thereof.

In witness that I claim the foregoing I have hereunto subscribed my name this 22d day of Nov., 1916.

JOHN F. O'CONNOR.
